Patented Aug. 23, 1927.

UNITED STATES PATENT OFFICE.

ALBERT C. FISCHER, OF CHICAGO, ILLINOIS.

EXPANSION JOINT.

Application filed August 21, 1926. Serial No. 130,686.

Preformed strips of expansion joint material as they are known to those acquainted with the construction of concrete and the like roadways are frequently open to objection due to inconvenience in handling prior to the installation of the same.

Owing to the necessary compressible and more or less plastic qualities that the expansion joint strip must have in order that it will properly function, and since these qualities are usually derived from the use of compositions, the materials of which being for the most part plastic certain inconveniences are experienced in handling the strips, particularly in warm weather, when, due to high temperatures, the strips become flabby and have a tendency to warp out of shape.

After the strips have been fabricated at the place of production they usually must be shipped to dealers, where they are carted to the job and distributed along the roadway so as to be handy for installing. All of this transporting makes it necessary to handle the strips several times, and each time care must be taken that the joints are not destroyed by breaking or warping, or otherwise departing from their intended preformed shape and dimensions, otherwise they cannot be properly installed.

Various ways have been devised to reinforce the strips, so to speak, so that they may be handled with the least possible inconvenience. According to the prior art one means resorted to has been the application of saturated felt sides to the preformed strip of compressible material which makes up the joint. Another means has been the application of burlap sides. Wire mesh has also been suggested for this purpose, the same being imbedded in the sides of the joint and sometimes internally imbedded. There are other attempts to meet these requirements but as far as my invention is concerned the means specified are most closely allied with the principle of my invention than any other methods.

In the accompanying drawing which I have selected for the purpose of illustrating the salient features of my invention Figure 1 is a perspective view of a portion of an expansion joint strip showing one method of reinforcing the same.

Figure 2 is a perspective view of a portion of a so-called tongue and groove expansion

joint strip, illustrating the application 55 of my invention.

Figure 3 is a similar view but showing how a staking means may be used in combination with the tongue and groove structure. 60

Figure 4 is a view similar to Figure 2 showing how an opening or openings may be provided for accommodating horizontal reinforcing bars or rods.

Referring now to the drawing in detail. 65 Figure 5 represents a preformed strip of expansion joint material which may be made of any material, suitable for the purpose, providing it has the inherent quality of compressibility. The strip in most cases will be preformed in lengths of 5 feet, in thicknesses varying from $\frac{1}{4}$ inch to 1 inch and about $\frac{1}{4}$ inches in depth. These dimensions are, of course, simply illustrative of the general characteristics of the joint and should not 70 be interpreted as controlling in every instance. However, regardless of the dimensions of the strip, according to one form of my invention I enclose the same with a plaster, which may be applied to only one side, or it may be 75 applied to opposite sides 6 and 7 as well as the crown 8 and the base 9, and while not shown as extending across the ends it may do so, and no doubt will in some cases, so that a complete envelop is provided for. 85

In Figure 2 the strip is preformed with a tongue 10 on one side and a groove 11 on the opposite side. This is a more or less common construction for expansion joints, and I have shown the same simply to indicate how 90 the plaster may be applied to this form of joint.

So far as the illustration shows, only the straight sides 12 and the tongue and groove are covered with the plaster, that is to say, 95 it does not extend across the base of the crown nor does it extend across the ends, although it may be applied to this extent without departing from the spirit of the invention as pointed out in the subjoining 100 claims.

In Figure 4 the strip 5 has side walls 15 and 16 of plaster and an opening 17 made in the thickness of the joint to accommodate a horizontal reinforcing rod or pin, which 105 will extend thru the joint and with its opposite ends imbedded in the concrete sections between which the joint is installed,

In using the term "plaster" to describe the material on the sides I intend that the term shall embrace any material or composition which may be applied in a liquid or 5 semi-liquid consistency and capable of hardening or drying under ordinary atmospheric conditions, and which will develop a hard non-pliable coating or layer capable of stiffening the strip to such an extent that it can- 10 not bend or sag when handled.

A material suited for this purpose may be ordinary Portland cement, providing it is applied in the form of a wash, so to speak, or a composition of cement and asbestos, or 15 gypsum, stucco, ordinary plaster, plaster of Paris, or any combinations of these materials with or without the use of fibre or the like filling material. The plaster material may be applied by a spray or by immersion, or a 20 brush may be used to apply it. For the most part they will be of a thinner consistency than such material as applied to walls is ordinarily expected to be, as it will not be necessary for me to make the layers very thick 25 in order to develop the necessary reinforcing qualities, and as a matter of fact it would not aid the functioning of the joint if a very thick wall of this kind of material was employed. 30 From this explanation it will be seen that I have eliminated the possibility of using such materials as bitumen or asphalt, or sheet material such as saturated felt, paper or paper substitutes. Such materials are not 35 classified as "plaster" in the ordinary accepted meaning of the word, and consequently where the term "plaster" is recited in the specification and claims it should be construed to embrace only such materials as 40 cement, asbestos, gypsum, stucco, ordinary plaster, plaster of Paris or the like, which will harden as a non-pliable layer.

I claim:

1. An expansion joint comprising a pre-formed compressible structure enclosed in a 45 jacket of plaster which is permanently rigid after hardening.
2. An expansion joint comprising a pre-formed strip of compressible material enclosed in a jacket of plaster which is permanently rigid after hardening. 50
3. An expansion joint comprising a pre-formed strip of compressible material having plaster applied to the side thereof, said plaster being permanently rigid after hardening. 55
4. A preformed expansion joint embodying in its construction an intermediate layer of compressible material surfaced on both sides with outer layers of plaster which is 60 permanently rigid after hardening.
5. An expansion joint comprising a pre-formed strip of compressible material having a tongue on one side and a groove on the opposite side and plaster on the side of said 65 strip, said plaster being permanently rigid after hardening.
6. A preformed expansion joint, comprising a boardlike body having a tongue on one side, a corresponding groove on the other 70 side, and a flat portion arranged to one side of said tongue and groove, said joint embodying in its construction a thickness of compressible material reinforced by a thickness of plaster which is permanently rigid 75 after hardening.
7. An expansion joint, comprising a pre-formed strip of compressible material having plaster applied to the side thereof, said plaster being permanently rigid after hardening and having fibrous material incorporated therein. 80

ALBERT C. FISCHER.
